A. PETERSEN

BRAIDING MACHINE

Original Filed Jan. 3, 1921

UNITED STATES PATENT OFFICE.

ANKER PETERSEN, OF WINTHROP, MASSACHUSETTS, ASSIGNOR TO AMERICAN WIRE-MOLD COMPANY, OF HARTFORD, CONNECTICUT, A CORPORATION OF CONNECTICUT.

BRAIDING MACHINE.

Application filed January 3, 1921, Serial No. 434,419. Renewed December 20, 1923.

To all whom it may concern:

Be it known that I, ANKER PETERSEN, citizen of the United States of America, and resident of Winthrop, in the county 5 of Suffolk and State of Massachusetts, have invented new and useful Improvements in Braiding Machines, of which the following is a specification.

This invention relates to braiding machines, and more particularly to an expandable condenser or die for equalizing the tension of the individual strands forming the braid. While the device forming the subject-matter of the present invention is 10 well-adapted for use in connection with various types of braiding machines, it is herein illustrated as applied to a machine of the general type disclosed in the patent to Petersen, No. 1,331,672, February 24, 1920, 15 to which patent reference may be had for a fuller disclosure of the details of such a braiding machine.

In braiding machines as commonly constructed, the individual strands for forming 20 the braid are supplied from carriers which are so moved relative one to another as to intertwine or braid the strands at the forming point. Usually each carrier is furnished with a tension device for its strand, 25 and the completed braid is drawn off from the forming point by a take-up arrangement that applies the desired tension to the braid.

With this arrangement the tension of 30 each strand within the finished braid depends upon the action of the individual tension devices on their respective strands, and there is no certainty that all the strands will pass into the braid under equal tension. 35 If variations occur in the tension of the strands forming a piece of braid, each strand will not impart its proportionate amount of strength to the braid, as the entire strain will fall upon the taut strands 40 and not upon the slack ones.

The primary object of the present invention, therefore, is to so improve a braiding machine, and more especially the forming die or condenser employed therein, as to 45 overcome the defects heretofore experienced

and thus produce braid having each of its strands under substantially equal tension and available for supporting its proportionate part of the load to which the braid may be subjected.

As one mode of attaining this object, the device disclosed in the accompanying drawings may be employed, and in which:—

Fig. 1 is a partial transverse vertical section of a braiding machine of usual form, 60 illustrating the invention as applied thereto;

Fig. 2 is a plan view of the parts shown in Fig. 1;

Fig. 3 is a vertical, diametral section to 65 large scale of the braiding arbor forming the subject matter of this invention;

Fig. 4 is a horizontal cross section of such arbor taken on the line *a*—*b* of Fig. 3;

Fig. 5 is a very much enlarged, fragmentary cross section similar to Fig. 4, illustrating further details of construction, 70 and;

Fig. 6 is a diagrammatic view to large 75 scale illustrative of the general mode of operation of the device of the present invention.

The main frame of the machine is provided with a bracket member 1 having a central hub portion 2. Within the opening in the hub portion 2 is fixed a hollow shaft or spindle 3. A sleeve 4 surrounds the spindle 3 and turns freely thereon. Secured upon the sleeve 4 by means of a key or in other suitable manner is a bevel gear 5 which rests upon the upper ends of the hub 2. 7 is a driving shaft mounted in a bracket 8 of the frame and having fixed thereon a pinion 10 which meshes with the bevel gear 5 for driving the same. Upon the sleeve 4 above the gear 5 is journaled 80 to turn a revolving frame 11 which supports the outer series of carriers and the strand guides not shown. The frame 11 is provided with a bevel gear 12 which also 85 meshes with the pinion 10, the arrangement being such that the frame 11 and the gear 5 turn in opposite directions. Fast upon the sleeve 4 above the frame 11 is the circular plate 13 which carries in suitable bear- 90

100

ings a series of thread-carrier drive rolls 17. Secured to the drive roll 17 is a friction roll 20 which engages a flexibly supported drive element 21^a carried by a supporting disk 21 fast upon the upper end of the fixed spindle 3.

The parts as thus far described are such as are common to braiding machines of a well known commercial type and it is therefore unnecessary to describe them herein in greater detail.

Secured within the upper end of the hollow spindle 3 in any desired manner, as by friction or positive holding means, is the 15 braiding die or condenser 30. This die comprises a substantially cylindrical sleeve-like body 31 having reduced diameters 32 and 33 at its opposite ends. The die is provided with an axial bore 34 through which the 20 braid may be drawn off as formed. A radial slot 35 extends outwardly from the bore 34 to the outer surface of the die, such slot being of a width substantially equal to the diameter of the bore 34. 37 is a 25 blade-like member loosely fitting within the slot 35 and provided upon its inner edge with an arcuate groove 38, the curvature of which is substantially like that of the inner wall of the bore 34. The outer edge 30 of the blade 37 has projecting therefrom a pair of lugs 39, 40, such lugs upon their adjacent sides overhanging to form the hook-like elements 41, 42, respectively. A bow spring 43 is arranged with its opposite 35 end seated beneath its members 41, 42, and with its central portion projecting out beyond the plane of the outer faces of the lugs 39, 40.

Upon the reduced portion 32 of the cylindrical body is secured a cap 44 which may be retained in position by a set screw or in other desired manner. The outer face of the cap 44 provides a substantially spherical surface 48 surrounding a central opening or bore 49, such bore being of substantially larger diameter than the bore of the body portion 31. The surface 48 serves to guide the strands which merge from the various thread carriers toward the bore 49, which latter constitutes the braiding or forming point of the machine. A collar 46 surrounds the reduced portion 33 of the body and may also be secured in place by a set screw.

The blade 37 extends somewhat beyond the lugs 39, 40, as indicated at 45, 47, respectively, and such extended portions are arranged to lie within the cap 44 and collar 46 respectively. The outer faces of the lugs 39, 40 are substantially straight and engage the edges of the cap and collar and thus the blade is retained within the slot but is permitted to have a slight movement in a radial direction therein. The die or condenser as thus formed is slipped down

into and is retained in the spindle 3, in which position the central portion of the spring 43 engages the inner surface of the spindle and thus serves to urge the blade 37 inward in a radial direction whereby to restrict and to a certain extent obstruct the bore 34.

S, S' indicate the individual strands of yarn passing from the several carriers of the two series and which merge and intertwine at the braiding point. The finished braid is indicated at B, such braid passing down through the hollow spindle after emerging from the lower end of the die 30, and passing to a suitable take-up device whereby the drawing off tension is applied thereto. A simple form of such take-up device is diagrammatically indicated in Fig. 1 wherein T is one of a pair of engaging rolls receiving its motion from a shaft T' and between which rolls the braid may pass. While this form of take-up is herein indicated as suitable for the purpose, it is to be understood that it is merely illustrative of one form of take-up or tension device and that any other and usual form might be employed.

In the operation of the device the various strands passing from the carriers come together at the center of the machine where they lie upon the surface 48 and then pass downwardly into the bore 49 in the cap 44. Within such bore the several strands intertwine to form the braid, the braid then passing down through the condenser as above described. As the several strands are subjected to individual tension devices which may not all exert the same tension thereon, it sometimes occurs that one or more strands may arrive at the braiding point in a somewhat slack condition.

In Fig. 6 is illustrated diagrammatically the formation of a three strand braid wherein one of the strands Z is shown as under less tension than the strands X and Y. Thus at the braiding point such strand may form a bight or slack loop 50 and if directly braided into the material in such condition such slack strand would fail to carry its due share of the load when the braid is subjected to tension. By the employment of the resiliently movable blade 37, however, the bore 34 is constricted to a certain extent whereby the braid in passing therethrough is compressed, which results in the pushing or stripping back of any such loose bight as indicated at 50. Such bight is thereby prevented from entering into the completed braid as the latter is drawn off and thus each strand of the completed braid is in proper condition to support its proper share of any load to which the braid may be subjected.

As it sometimes happens that slubs or other imperfections occur in the yarn it is

desirable that the wall of the braiding die be capable of yielding somewhat for the passage of such obstructions, it being considered that the passage of such imperfections is preferable to the breaking of the braid or of a strand thereof, as such breakage involves a rather difficult and tedious process of threading up the machine anew.

By mounting the blade 37 as a movable element pressed inwardly by means of a spring it is possible for such blade to move outwardly whereby to permit the passage of abnormal bunches in the braid, or yarn.

Although in Fig. 6 a three strand braid has been illustrated for the sake of clearness in illustration, it is understood that the machine herein disclosed is intended for making braid having a large number of strands as for example 32, although the present invention is not in any manner restricted to the use with such a form of machine but may be found of general utility in any braiding machine to which it may be applied.

Having thus described the invention in a preferred form of the same together with the mode of operation thereof, what I claim and desire to secure by Letters Patent of the United States is:

1. A braiding die for braiding machines comprising a substantially cylindrical body portion having an axial bore for the passage of braid, and a radial slot intersecting said bore, an elongated blade member loosely engaging said slot, said blade member having an arcuate groove along its inner edge for contact with the peripheral surface of the braid and a pair of lugs upon its outer edge, and a bow spring engaging said lugs whereby resiliently to urge said blade toward the braid.

2. A braiding machine comprising a hollow spindle, series of braiding carriers revolvable about said spindle forming a braid, and a braiding die or condenser seated within said spindle and having a cap at its upper end provided with an opening constituting the braiding point, said die having an axial bore aligned with said opening for the passage of the braid, a member movable into said bore for obstructing the free passage of braid therethrough, and a spring for resiliently urging said member inwardly, said spring reacting against the inner wall of said spindle.

3. A braiding die for braiding machines comprising a cylindrical body having an axial bore, said body having portions of reduced diameter at its ends and having a radial slot extending from end to end, a blade member loosely engaging said slot, lugs outstanding from the outer edge of said blade member adjacent to its ends, a collar engaging the reduced portion of said body

at one end, and a cap engaging the reduced portion of said body at the other end, said cap having a central opening aligning with the bore in the body and constituting the braiding point, said collar and cap overlying the respective ends of said blade beyond the lugs thereon for retaining the same within the slot.

4. In combination with a braiding machine having a plurality of thread carriers and means for moving the carriers to cause the strands to braid together as they approach the braid forming point, a braid embracing die supported adjacent the braid forming point and having a channel for the passage of the braid therethrough and a slot extending outwardly from the channel, a blade mounted in said slot for movement toward and from the channel, and yielding means for urging the blade inwardly toward the channel to restrict the channel and thereby retard the passage of slack strands of the braid through the die.

5. In combination with a braiding machine having a plurality of strand carriers and means for moving the carriers to cause the strands to braid together as they approach the braid forming point, a cylindrical die supported adjacent said braid forming point and having a channel for the passage of round braid therethrough, movable means for restricting said channel and having an arcuate face that engages the braid to retard the passage of slack strands of the braid therethrough, and a spring for urging the movable means into intimate engagement with the braid.

6. In combination with a braiding machine having a hollow spindle through which the completed braid passes, a cylindrical die mounted within said spindle and having a channel for the passage of round braid, movable means for restricting said channel to retard the passage of slack strands of the braid therethrough, and a spring confined between the inner wall of said spindle and said means for urging the movable means into intimate engagement with the braid.

7. In combination with a braiding machine having a hollow spindle through which the completed braid passes, a cylindrical die mounted within said spindle and having a channel for the passage of round braid and a slot extending radially outwardly from the channel, a presser blade mounted within the slot for sliding movement toward the channel and having an arcuate braid engaging edge, and a spring for holding said blade in firm engagement with the braid.

Signed by me at Boston, Mass. this 18th day of December 1920.

ANKER PETERSEN.
